UNITED STATES PATENT OFFICE.

FERRAND F. ELLIS, OF VERNON, NEW YORK.

SOLDERING DEVICE.

SPECIFICATION forming part of Letters Patent No. 279,234, dated June 12, 1883.

Application filed October 26, 1882. (No model.)

To all whom it may concern:

Be it known that I, FERRAND F. ELLIS, of the town of Vernon, in the county of Oneida, in the State of New York, have invented new and 5 useful Improvements in Soldering Devices, of which the following, taken in connection with the accompanying drawings, is a full, clear, and exact description.

This invention relates to that class of soldering devices which are usually termed "capping-irons," and are employed for soldering the caps on tin cans used for preserving fruit, &c.

The invention consists in an improved construction and combination of the constituent 15 parts of the capping apparatus, whereby the same is rendered more convenient and efficient in its operation, as hereinafter more fully explained, and specifically set forth in the claims.

In the accompanying drawings, Figure 1 is 20 a vertical transverse section of my invention arranged to be operated by steam or other power. Fig. 2 is a longitudinal transverse section on line $\alpha\alpha$, and Fig. 3 is a plan view of a can to be capped.

25 Similar letters of reference indicate corresponding parts.

Upon a suitable table or work-bench, C, is erected a post or pedestal, D, which supports in a horizontal position a furnace, F, in the 30 form of an elongated chamber, which is open at one end and has a partition, l , extending from said end part way toward the closed end, and thereby forming two passages, meeting at the interior of the chamber. A gas or vapor pipe, 35 G, having a suitable burner projecting into one of the aforesaid passages of the furnace F, furnishes the flame, which circulates through the furnace and escapes through the other passage, as indicated by arrows in the drawings. At 40 the junction of the said passages the furnace is formed with a vertical cylindrical enlargement, through which is extended a cylindrical block, H, of metal or other suitable heat-conducting material, said block being of a smaller diameter than the furnace and arranged concentric with the same, so as to form around the block an annular passage, which, by the extension of the partition l to the block H, is made to constitute the continuation of the before-described 45 passages through the furnace.

Vertically through the center of the block is

extended a tube or hollow spindle, S, to the lower extremity of which is attached an annular block of copper, A, the lower edge of which is of a diameter and of proper shape to encompass the cap I of the can shown in Fig. 4 of the drawings, and run the solder around said cap, in the manner hereinafter explained.

55 The spindle S may be either fitted to revolve in the block H or fixed thereon, and the block arranged to revolve in the furnace.

Longitudinally through the spindle S is extended a rod, a , which is suspended from a collar, c , attached thereto and resting loosely on the upper end of the spindle.

65 To the upper end of the spindle is attached a handle, B, which has a vertical cylindrical cavity, d , in range with the axis of the spindle. In said cavity is placed a spring, e , which presses on the collar c of the rod a , for the 70 purpose hereinafter described.

To the lower extremity of the rod a is attached a combined soldering and centering point, b , which projects below the lower edge of the copper A, and is adapted to enter the 75 usual vent, m , in the center of the cap of the can. (See Fig. 3 of the drawings.) The entrance of the point b in the vent m serves to hold the can in its requisite concentric position under the soldering-tool, so as to bring 80 the annular bottom edge of the soldering-iron A into the usual annular depression around the opening of the can to be capped.

Underneath the described soldering-tool is arranged a movable table or support, E, for 85 the can to be capped. Said table is carried upon an arm, n , connected with a lever, o , which is fulcrumed on a suitable support, p , attached to the under side of the work-bench. By means of the lever o the table E can be 90 raised and lowered to carry the can resting thereon to and from the soldering-tool A. The table is lowered for applying thereto the can to be capped, and for removing the same after it is capped.

95 k represent racks attached to the top of the work-bench, and of proper height to carry the solder r in a convenient position for moving it up to and from the soldering-tool A.

The spindle S is sustained in its vertical position by arms M M, extended from the pedestal D, and provided with suitable bearings en-

compassing the spindle. A driving-shaft, O, is stepped in the upper end of the pedestal, and is provided with a gear or spur wheel, N, which engages the pinion *f* of the spindle, and thus transmits motion to said spindle.

5 If desired, pulleys and a belt may be substituted for the gears.

The operation of my invention is as follows: After the gas or vapor burner in the furnace F is lighted and the block H heated sufficient to transmit to the copper A the requisite heat for melting the solder, the can to be capped is placed on its support E, as represented by dotted lines in Fig. 1 of the drawings. The cap 10 being placed in position on the can, the support E is raised to carry the can up to the soldering-tool. The solder *r* is then brought in contact with the heated copper A sufficiently to run the requisite amount of solder around the 15 usual annular indentation, *s*, in which the crimped edge of the cap rests. The spindle S, being in the meantime revolved, causes the revolving copper A to run the solder around the edge of the cap. During this operation the 20 rod *a* is pushed upward by the collision of its projecting point *b* with the top of the cap, and said point is held in the usual vent, *m*, in the center of the cap by the pressure of the spring *e* on the upper end of the rod *a*, thereby firmly 25 holding the cap in position while soldering it on the can in the manner aforesaid. After this is completed, the table E, with the can seated thereon, is lowered by means of the lever *o*. This allows the rod *a* to drop until 30 rested by the encounter of its collar *c* with the end of the spindle S. The solder is then 35

applied to the projecting point *b* of the rod *a*, and the can brought up to it to run the solder over the vent *m* of the cap, thus capping and sealing the can in a most convenient, reliable, 40 and expeditious manner.

Having described my invention, what I claim as new, and desire to secure by Letters Patent, is—

1. In combination with the table E and furnace F, the soldering-iron A, arranged to rotate in said furnace, and mechanism for imparting rotary motion to said soldering-iron, substantially as shown. 45

2. In combination with the furnace F and spindle S, the copper A, secured to the end of the spindle, and the heating-iron H, enveloping the copper, substantially as shown and described. 50

3. In combination with the furnace F, the spindle S, passing into the furnace and provided with the copper end A, the rod *a*, arranged to reciprocate in the spindle and provided with the copper point *b*, and the heating-iron H, enveloping the spindle and its coppered end, substantially as and for the purpose set forth. 55

In testimony whereof I have hereunto signed my name and affixed my seal, in the presence of two attesting witnesses, at Syracuse, in the 60 county of Onondaga, in the State of New York, this 12th day of October, 1882.

FERRAND F. ELLIS. [L. S.]
